UNITED STATES PATENT OFFICE

BEN B. MANASTER, OF CHICAGO, ILLINOIS

DESIGN FOR A BELT BUCKLE CONNECTER OR THE LIKE

Application filed September 24, 1932. Serial No. 45,054. Term of patent 7 years.

To all whom it may concern:

Be it known that I, BEN B. MANASTER, a citizen of the United States, residing at Chicago, in the county of Cook and State of Illinois, have invented a new, original, and ornamental Design for a Belt Buckle Connecter or the like, of which the following is a specification, reference being had to the accompanying drawing, forming part thereof.

The single figure is a perspective view of the belt buckle connecter showing my new design.

I claim:

The ornamental design for a belt buckle connecter or the like substantially as shown.

BEN B. MANASTER.
